H. GOODACRE & A. H. ALLEN.

MAT HOLDER.

APPLICATION FILED FEB. 2, 1917.

1,241,957.

Patented Oct. 2, 1917.

FIG. 1.

10 20 INVENTORS
22 Harry Goodacre
23 Albert H. Allen
by Wright & Dunn Quincy May ATTYS.

UNITED STATES PATENT OFFICE.

HARRY GOODACRE AND ALBERT H. ALLEN, OF WAKEFIELD, MASSACHUSETTS, ASSIGNEES TO HEYWOOD BROTHERS & WAKEFIELD COMPANY, OF WAKEFIELD, MASSACHUSETTS, A CORPORATION OF NEW JERSEY.

MAT-HOLDER.

1,241,957.

Specification of Letters Patent.

Patented Oct. 2, 1917.

Application filed February 2, 1917. Serial No. 146,278.

To all whom it may concern:

Be it known that we, HARRY GOODACRE, a subject of the King of Great Britain, and ALBERT H. ALLEN, a subject of the King of 5 Great Britain, both residing at Wakefield, in the county of Middlesex and State of Massachusetts, have invented new and useful Improvements in Mat-Holders, of which the following is a specification.

10 This invention has for its object to provide improved means for yieldingly engaging a mat with the running-board of an automobile, and at the same time confining and protecting the margin of the mat, so 15 that the mat will retain its predetermined shape and present a neat and desirable appearance.

The invention is embodied in the improvements which we will now proceed to 20 describe and claim.

Of the accompanying drawings forming a part of this specification,—

Figure 1 is a perspective view of a mat holder embodying the invention.

25 Fig. 2 is a transverse section of the holder, the mat engaged therewith, and a running-board with which the holder is engaged.

Fig. 3 is a fragmentary view, similar to 30 a portion of Fig. 2, showing a different form of running-board.

Fig. 4 is a view similar to a portion of Fig. 2, showing a relatively thin running-board with a downwardly projecting flange at its outer edge.

35 Fig. 5 is a view similar to Fig. 2, showing a modification.

Fig. 6 is an end view, showing the frame provided with teeth or spurs engaging the upper side of the running-board.

40 The same reference characters indicate the same parts in all the figures.

In the drawings, 12 represents an open frame formed to surround the margin of a mat 13, and to bear on the upper side of a 45 running-board 14. The frame, which is preferably composed of a strip of steel, suitably bent and welded together at its ends, is provided with a contracted holding-down upper edge 12^a adapted to overhang 50 marginal portions of the mat and confine the same against upward movement.

The frame is provided with a plurality of resilient members which are preferably flat-sided strips of steel, each including an

upper portion 15, extending across the lower 55 portion of the frame and suitably engaged with the rear and front sides thereof, necks 16 bent downwardly from said upper portion at the front side of the frame and adapted to extend across the outer edge of 60 the running-board, and clamping-arms 17 extending rearwardly from said necks and adapted to coöperate with the under side of the running-board in yieldingly securing 65 the holder to the board.

The upper portions 15 are preferably provided at their inner ends with upstanding ears 15^a connected by rivets 18 with the rear side of the frame, the front side of the frame being preferably provided with apertures 19 which are preferably narrow slots, 70 through which the upper portions 15 pass loosely.

Each resilient member is therefore adapted to be secured to the frame by a single 75 rivet, its loose engagement with the front side of the frame enabling the upper portions 15 to be flexed downwardly and bear yieldingly against the upper side of the running-board, as indicated by Fig. 2, to 80 assist the frictional engagement of the holder with the running-board.

The apertures 19 are relatively near the lower edge of the frame and are sufficiently spaced from said lower edge to permit the 85 projecting portions of the upper members 15 to bridge a raised portion 14^a on the upper side of the running-board, as indicated by Fig. 3.

The clamping-arms 17, which may be 90 called primarily clamping-arms, are preferably provided with supplemental clamping-arms 20, which may be flat-sided steel strips attached at their rear ends by rivets 21 to the primary arms 17 and projecting 95 forward, the free ends of the supplemental clamping-arms being spaced from the necks 16 so that they may engage the inner side of a flange 14^c on a relatively thin pressed metal running-board 14^b, as indicated by 100 Fig. 4. The supplemental spring also bears on the under side of a relatively thick running-board, as shown by Fig. 2, and thus increases the frictional hold.

In the embodiment of the invention shown 105 by Fig. 5, the upper portions 15 of the resilient members are connected by rivets 22 with ears 23 formed on the lower por-

tions of the rear and front sides of the frame 12.

In each embodiment of the invention, the upper portions 15 of the resilient members 5 are adapted to support a mat engaged with the frame, and to prevent the mat from falling through the frame when the mat and holder are assembled and ready for sale or use, said upper portions coöperating 10 with the contracted edge 12^a in confining the nut against accidental sidewise displacement in either direction. It will be understood, however, that the mat may be forcibly displaced through the opening surrounded by 15 the edge 12^a.

The free ends of the clamping-arms 17 may be connected by a transverse member 24, which may be a flat-sided metal strip secured to the arm 17 by rivets 25, the member 24 being adapted to bear on the under side of the running-board and thus increase 20 the frictional hold. The ends of the member 24 may be slightly curved downwardly, as indicated by Fig. 1, to facilitate the application of the holder to the running-board, and the said member may be transversely inclined, as indicated by Fig. 2, for the same purpose.

The clamping-arms are normally held 30 yieldingly in close proximity to the upper portions 15 of the resilient members, when the holder is not in use, as indicated by Fig. 1, their resilience being such that they are adapted to coöperate either with a relatively thin running-board 14^b, or a relatively thick running-board 14. The supplemental arms 20 engaging the flange of a relatively thin running-board compensates for the decreased frictional hold on the under side of the running-board by preventing 35 removal of the holder from the running-board until the supplemental arms are manually depressed from the position shown by Fig. 4.

45 The frame may be provided at its lower edge with downwardly projecting teeth or spurs 27 adapted to engage the upper surface of the running-board, and preferably formed by serrating the end portions of the frame 50 as indicated by Fig. 6, said spurs preferably projecting below the edges of the front and rear sides of the frame.

We claim:

1. A mat holder comprising an open 55 frame formed to surround the margin of a mat and bear on a running-board, and having a contracted holding-down upper edge, and a plurality of elongated resilient members, including upper portions extending 60 across the lower portion of the frame and engaged with the rear and front sides thereof, said upper portions being arranged to bear on the under surface of a mat inserted in the frame, necks bent downwardly 65 from said upper portions and adapted to

extend across the outer edge of a running-board, and clamping-arms extending rearwardly from said necks and adapted to co-operate with the under side of the running-board in yieldingly securing the holder to the board, the upper portions of said members being adapted to coöperate with said holding down edge in preventing accidental sidewise displacement of a mat in either direction. 70

2. A mat holder comprising an open frame formed to surround the margin of a mat and bear on a running-board, and having a contracted holding-down upper edge, and a plurality of elongated resilient members, including upper portions extending across the lower portion of the frame and engaged with the rear and front sides thereof, necks bent downwardly from said upper portions and adapted to extend across the outer edge of a running-board, primary clamping-arms extending rearwardly from 85 said necks, and supplementary clamping-arms attached to the free extremities of said primary arms and extending forward therefrom, said supplemental arms being adapted to bear on the under side of a relatively thick running-board, and their free ends being spaced from said necks and adapted to engage a flange on a relatively thin running-board. 90

3. A mat holder comprising an open frame formed to surround the margin of a mat and bear on a running-board, and having a contracted holding-down upper edge, 100 and a plurality of elongated resilient members, including upper portions extending across the lower portion of the frame and engaged with the rear and front sides thereof, necks bent downwardly from said upper portions and adapted to extend across the outer edge of a running-board, clamping-arms extending rearwardly from said necks and adapted to coöperate with the under side of the running-board in yieldingly securing the holder to the board, the upper portions of said members being adapted to support a mat, and a transverse member attached to and connecting the free ends of said clamping-arms and adapted to bear on 115 the under side of the running-board. 110

4. A mat holder comprising an open frame formed to surround the margin of a mat and bear on a running-board and having a contracted holding-down outer edge, 120 and apertures in its outer side near the lower edge thereof, and a plurality of elongated resilient members rigidly attached to the inner side of the frame and including upper portions extending across the frame near 125 the lower edge thereof and passing loosely through said apertures, necks bent downwardly from the said upper portions and adapted to extend across the outer edge of a running-board, and clamping-arms ex-130

tending rearwardly from the said necks and adapted to coöperate with the under side of the running-board in yieldingly securing the holder to the board, the said apertures being spaced from the lower edge of the frame and holding the upper portions of said resilient members in position to bridge a raised member on the upper side of a running-board.

5. A mat holder comprising an open frame formed to surround the margin of a mat and bear on a running-board, said frame having a contracted holding-down

upper edge and spurs at its lower edge adapted to engage the upper side of the running-board, and resilient securing means engaged with said frame, and including clamping-arms adapted to coöperate with the under side of the board in yieldingly pressing said spurs against the upper side of the board.

10 In testimony whereof we have affixed our signatures.

HARRY GOODACRE.
ALBERT H. ALLEN.
